UNITED STATES PATENT OFFICE

WALTER E. KROTEE, OF PHILADELPHIA, PENNSYLVANIA

INSULATED DRIVING CONNECTION

Application filed July 26, 1929. Serial No. 381,372.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

This invention relates to an insulated driving connection especially adapted for acoustic members.

In certain classes of sound apparatus such as those employed in locating the source of sound of a moving object, for instance, an airplane, the horns are mounted on a support for movement in azimuth and elevation. In order to damp out any sound vibrations which arise from metallic actuating parts or electrical apparatus on the support it has been proposed to form a bearing of a sound damping material. Since the mechanism for moving the sound apparatus in elevation must be directly connected thereto the bearing must be of a character to establish a driving connection between the parts.

The purpose of the present invention is to provide a novel arrangement of an insulated driving connection in which the insulation may be adjusted to compensate for shrinkage and its assembly facilitated.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Fig. 1 is a longitudinal sectional view on the line 1—1 of Fig. 2 of a bearing, showing the improved insulated driving connection.

Fig. 2 is a sectional view on the line 2—2 of Fig. 1.

Referring to the drawings by numerals of reference:

There is shown a support 5 for mounting a member 6 which is to be driven through a sleeve 7 on which is secured a gear segment 8.

The driven member 6 which represents an acoustic horn forming part of an apparatus

for locating a source of sound as disclosed in Patent No. 1,774,826 of September 2, 1930, is inserted through the sleeve and is supported thereby through a bushing 9 of an insulating material.

For the purpose of establishing a driving connection between the member 6 and the sleeve, the bushing is made in sections 10—10 which are placed between alternately disposed, longitudinal extending fins 11 and 12 formed respectively on the outer wall of the driven member 6 and on the inner wall of the sleeve 7. Two of the sections 10 are placed between adjacent fins and separated by a wedge 13 which is radially movable through a cap screw 14 threaded into the member 6. The sleeve is provided with apertures 15 in alignment with the screws 14 whereby the wedge may be moved to compress the insulation against the fins and insure a driving connection in which all play is removed.

As the most efficient type of insulation to be employed under the circumstances is one having a resilient body such as rubber, the present arrangement will facilitate assembly and avoid the necessity for precise dimensioning of the parts involved.

I claim:

1. In a driving connection, a support, a sleeve mounted in the support and having internal longitudinally extending fins, an acoustic member within the sleeve having external longitudinally extending fins, the fins of the sleeve and member being alternately arranged, a pair of sound damping members between adjacent fins, a wedge separating the sound damping members, cap screws in each wedge threaded into the acoustic member and means for rotating the sleeve.

2. In a driving connection a support, a sleeve mounted on the support, an acoustic member to be driven from the sleeve, sound damping material between the sleeve and driven member, means on the sleeve and driven member in engagement with said material, radially movable means for compressing the material and means for driving the sleeve.

WALTER E. KROTEE.
